CAKE DECORATOR

Filed May 17, 1928

UNITED STATES PATENT OFFICE.

ONOFRIO GENOVA, OF NEWBURGH, NEW YORK.

CAKE DECORATOR.

Application filed May 17, 1928. Serial No. 278,605.

This invention relates to improvements in the type of implement employed in the art of confectionary and cake making, particularly the decoration of same.

5 The primary object of this invention is to provide a device of the above mentioned character adapted to form a multiplicity or series of multi-colored sectors of confectioner's icing for more easily writing on confectionery, such as cakes and the like.

Another object of this invention is to provide a device of the above mentioned character, which may be easily manufactured, and which is easy, simple and effective in operation.

15 Other objects and advantages of this invention will appear during the course of the following description, forming a part of this specification, in which, Figure 1 is a fragmentary plan view of the invention showing the manner in which the device is arranged for use in the cake industry.

Figure 2 is a longitudinal plan view of the invention showing the parts arranged prior 25 to being placed in position for operation. And Figure 3 is a cross-sectional view taken on lines 3—3 of Figure 2, showing the manner in which the parts of the device are assembled.

In the drawing forming a part of this specification in which like reference numerals refer to like parts throughout the same, attention is first directed to Figure 2 in which the numeral 5 designates an elongated conical-shaped member formed of a series of radially 30 extending fins 6, from the axis point 7. The fins 6, are wider at the uppermost end of the device 5, than at the lower end as more clearly shown in the Figure 2. The series of fins 6, may be formed by even or uneven numbers 35 of fins extending radially from a point which is equi-distant from the lateral edges of the fins 6.

Secured to the uppermost portion of the series of radially extending fins 6, is a handle 45 8, which is U shaped and the ends of the U shaped handle 8, may be secured to any pair of oppositely extending radial fins 6.

A follower 9, may be provided for the elongated conical-shaped member having formed 50 thereon a series of slots 10, formed therein to receive the radially extending fins 6. The radially extending slots 10, of the follower 9, form sectors 11, which closely fit the radially extending fins 6, at the edge portions of 55 the sectors 11. Each of the sector shaped followers 11, are reinforced by radially ex-

tending ribs 12, in order to form a more rigid structure which will not become twisted through use and operation of the device.

As shown in Figure 2 the follower 9, is 60 slidably positioned on the elongated conical device 5, so that the followers 11, having the slots 10, may be received in the openings formed by the radially extending fins 6. As the follower 9, is moved longitudinally in respect to the elongated conical device 5, the slots 10, increase and decrease respectively as the width of the radially extending fins 6, is greater at the uppermost portion of the device 5, than at the lowermost portion, thereby 65 forming fins which taper downwardly so that the device may be placed in the conventional form of confectioner's writing bag 13, having a metal tip 14, open as at 15, to allow the contents placed within the bag to pass there- 70 through.

For a consideration of the operation of the device it may be well to take this opportunity to set forth some of the ways in which the device may be employed. For instance, 80 in the art of confectionery making it has heretofore been customary to use the bag 13, having the metal tip 14, for writing upon or decorating cakes and other confectionery, by placing icing or the like in the bag 13, and 85 then squeezing same causing the icing to pass through the opening 15, of the metal tip 14. In forming multi-colored decorations on cakes and confectionery difficulty has been experienced in placing the different colors of 90 icings in the bag 13. This invention overcomes the above mentioned difficulty by using an implement 5, having radially extending fins 6, which form sector shaped openings for receiving the different colors of icings which 95 may be placed in the bag 13, after which the operator securely holds the follower 9, in his left hand while he grasps the handle 8, with his right hand and pulls upwardly, thereon to cause the icings placed in the openings between the radial fins 6, to be moved from the device 5, in substantially the same position that they assume in place upon the device 5.

The icing may be placed in the grooves between the radially extending fins 6, by using 105 a knife or other implement which will cause the icing to be smoothly spread in the grooves between the radially extending fins 6. The follower 9, is placed in position in respect to the device 5, as shown in Figure 2 prior to the 110 filling of the device 5, with different colored icings. The next step includes the placing of

the device 5, with the icings in the bag 13, and then removing the icings in the device 5, by the use of the follower 9, as heretofore described. After the icing is placed in the bag 5 in this manner the usual operation of squeezing the bag so that the contents therein may be caused to pass through the opening 15 of the metal tip 14. The icings placed in the bag are passed through the opening and the device is 10 manipulated to decorate confectionery such as cakes and the like, either in the form of writing or decoration.

While there is herein shown and described the preferred embodiment of the present invention, it is nevertheless to be understood that minor changes may be made therein without departing from the spirit and scope of the invention as claimed.

What I claim is:

- 20 1. In a confectionery implement, a series of radially extending fins, having their inner edges secured to a central point and their outer edges tapered longitudinally and forming a cone, a handle secured to the uppermost edges of the radially extending fins and a follower slidably mounted on the radially extending fins.
- 25 2. In a confectionery implement, of the type described a series of radially extending fins being wider at their uppermost portion, said fins being secured together at the innermost edges, a handle secured to the upper edges of a pair of oppositely and radially extending fins and a follower slidably positioned on the radially extending fins.
- 30 3. In a confectionery implement, of the above mentioned character, a series of radially extending fins, secured together at

their innermost edges, said radially extending fins tapering in width from the uppermost 40 portion to the lowermost portion, a handle secured to a pair of opposite radially extending fins, a follower slidably mounted on the radially extending fins, having slots for receiving the radially extending fins, and reinforcing 45 ribs formed on the follower to strengthen the portions of the follower between the radially extending slots.

4. In a confectionery implement, of the above mentioned character, a series of elongated radially extending fins having their outer edges longitudinally tapered to form a cone, secured together along their inner longitudinal edges, a handle secured to a pair of opposite radially extending fins, a follower 55 slidably mounted on the radially extending fins having radially extending slots for receiving the radially extending fins and reinforcing ribs formed on the follower between the radially extending slots.

5. In a confectionery implement, of the above mentioned character, a series of elongated radially extending fins, tapering in width from the uppermost portion to the lowermost portion, said radially extending fins 65 being secured together along their longitudinal edges, a handle of inverted U shape, having its ends secured to a pair of opposite radially extending fins, a follower slidably mounted on the radially extending fins, having radially extending slots for receiving the radially extending fins, and reinforcing ribs formed on the follower between the radially extending slots.

In testimony whereof I affix my signature.
ONOFRIO GENOVA.
